UNITED STATES PATENT OFFICE.

EDWARD Z. MARKSBERRY, OF LUDLOW, KENTUCKY, AND JOSEPH J. SANREGRET, OF CINCINNATI, OHIO.

GUARD FOR MACHINES.

1,402,630.

Specification of Letters Patent.

Patented Jan. 3, 1922.

Application filed November 2, 1918. Serial No. 260,886.

To all whom it may concern:

Be it known that we, EDWARD Z. MARKSBERRY and JOSEPH J. SANREGRET, citizens of the United States, and residents of Ludlow, 5 in the county of Kenton and State of Kentucky, and Cincinnati, in the county of Hamilton and State of Ohio, respectively, have invented certain new and useful Improvements in Guards for Machines, of 10 which the following is a specification.

Our invention relates to guards, and its object is to prevent the injury to the operators of machines and more especially of power presses.

15 Our invention consists in the combination of parts and in the details of construction and arrangement of parts as will hereinafter be more fully described and claimed.

In the drawing:

20 Fig. 1 is a front view of a power press with our invention applied thereto;

Fig. 2 is an end elevation of the lower part of the apparatus; and

Fig. 3 is a similar view of the upper part.

25 As we prefer to construct our invention, there is a flat base 1 adapted to rest on the bed 2 of the press, and which has standards 3 and 4 near its opposite ends supporting an inverted channel 5, while another channel 6 30 with its open side upward is fastened to the base 1 vertically under the channel 5; these channels 5 and 6 extending the full length of the base 1 across the front of the press and, as here shown, extending past the left-hand side of the press. These channels thus 35 form a track for the gate 7 which is made up of a bar 8 parallel with the track, flanked at front and rear by upright plates 9 and 10, respectively, which extend above and below 40 the bar 8 and have between them the rollers 11 and 12 bearing in the channels 5 and 6, respectively, and journaled in these plates 9 and 10. There is a set of these plates 9 and 10 and rollers 11 and 12 at each end of the 45 bar 7 which is located somewhat below the middle of the structure, leaving room for the connecting rod 13 to swing up and down between the plates 9 and 10 and having its end part pivoted between the right-hand set of 50 plates 9 and 10 by the pivot 14.

The end of the driving shaft 15 at the left side of the press has the crank 16 fixed to it by means of a cap-screw 17 extending through a radial slot 18 in the crank into the 55 center of the shaft. There is also a dowel-

pin 19 fixed in the end of the shaft and extending into the slot 18. The pitman 20 is preferably made up of a flat bar twisted near its middle so that its upper part presents a flat side against the crank 16 60 to which it is pivoted by means of the bolt 21; and the lower end part of the pitman 20 is so positioned that it receives through it the rearwardly projecting wrist of the double crank 22 which is fulcrumed in a 65 bracket 23 fixed to the end part of the base-plate 1 to the rear of the gate and its track. The pivot bearings of this pitman 20 at both ends are made slightly loose, so that the pitman 20 may swing freely throughout 70 its length both with the crank arm 16 and with the crank 22. The forwardly projecting wrist of this crank 22 has the left-hand end part of the connecting rod 13 pivoted to it. The rear and front parts of this crank 75 22 have an angular displacement from each other of about ninety degrees, so that the rear part of the crank may swing up and down while the forward part swings across the press. 80

When the treadle (not shown) is depressed to cause the driving shaft 15 to make one complete revolution, this shaft will through the medium of the crank 16, pitman 20, crank 22 and connecting rod 13, 85 cause the gate 7 to travel to the right in front of the space through which access is had to the die 24; and this travel to the right will be so rapid that it will push the operator's hand or arm into a safe position before 90 the punch 25 has reached the die 24. This will occur during the first half of the revolution of the shaft 15 and then during the remaining half the gate 7 will be pulled to the left again leaving the space clear. 95

The crank 16, by means of its slotted attachment to the shaft 17, may have its throw adjusted to vary the length of travel of the gate 7 as may be desired. Also, we prefer to attach the base-plate 1 of the device to 100 the bed 2 of the press by a single cap-screw 26 through a front-to-rear slot 27 in the base-plate so that the rear edge of the base-plate may lie against the front edge of the die 24 whatever may be the front-to-rear location of the die, which, of course, varies according to the size and particular construction of the die. Preferably, the structure should be amply long to avoid very close approach of the gate to the standard 110

4 at the right. Thus, there is not even the chance of slight injury to the operator's hand or arm which may be caused by catching it between the gate and the framework. 5 With such a guard having the gate travelling transversely of the machine, it is thus possible to avoid any catching of any part of the person. This is much safer than where the moving part travels up and down 10 with the chance of catching the operator between the guard and the lower part of the press. Also, by having the gate moved positively by the shaft 15 that operates the punch, there is no chance of the punch operating without operating the guard or gate. 15 This is not the case with machines having the guard operated by some attachment to the treadle that operates the clutch; because frequently owing to some defect in the 20 mechanism the punch may make two or more complete strokes for each operation of the clutch. Where the guard is controlled by the means that operates the clutch, the guard would not be in position 25 for the second or subsequent strokes of the punch and the operator is extremely liable to be caught. An advantage of our present invention lies in its extreme simplicity and ease of attachment and adjustment to practically any punch press to which it may be desired to apply it, whether the press be vertical or inclined. Also, it will be understood that the device is susceptible to some slight modification in adapting it to different presses. 30 Thus, for instance, we have used the terms "right" and "left" specifically in describing the example herein, and other details of this example have been more or less specifically described; but it will be understood that our invention is applicable in other positions relative to the machine on which it is used in order to meet the various requirements encountered in applying our invention to various kinds of machines, not 35 only to punch presses but in any other power driven machine where a guard is required. Accordingly, we do not wish to be understood as being limited to the precise examples herein set forth, but what we claim 40 is new and desire to secure by Letters Patent is:

1. A guard for a machine comprising a gate, rollers on the top of said gate, rollers on the bottom of said gate, an inverted channel extending transversely of said machine and receiving the rollers on said top, a channel extending along under said inverted channel and receiving the rollers on the bottom of said gate, a double crank fulcrumed on said machine, an element connecting one member of said crank to said

gate, a crank arm fixed to a rotatable part of said machine, and an element connecting the other member of said crank to said crank arm. 65

2. In combination with a machine having a rotatable part, a transversely movable gate, a support for said gate, a crank arm attached to said rotatable part, said crank arm being slotted where it is attached to 70 said part, whereby its throw may be adjusted, a crank fulcrumed on said support near said gate, an element connecting said crank to said gate, a pitman connecting said crank to said crank arm, and means adjustably attaching said support to said machine. 75

3. A guard for a machine comprising a base plate, a channel fixed along said base plate with its open side upward, standards fixed on said base plate, an inverted channel fixed on said standards over the aforesaid channel, a gate, rollers on the bottom and on the top of said gate, bearing in the respective channels, a double crank fulcrumed on said base plate near one end thereof, a connecting rod connecting said gate to one member of said crank, a crank arm attached to a rotatable part of said machine, a pitman connecting said crank arm to the other member of said crank, said base plate having a slot, and fastening means extending through said slot into a part of said machine, permitting said base plate and the parts carried thereby to be adjusted relatively to said machine. 85 90 95

4. A guard for a machine comprising a base plate, a channel fixed along said base plate with its open side upward, standards fixed on said base plate, an inverted channel fixed on said standards over the aforesaid channel, a gate, rollers on the bottom and on the top of said gate, bearing in the respective channels, a double crank fulcrumed on said base plate near one end thereof, a connecting rod connecting said gate to one member of said crank, a crank arm attached to a rotatable part of said machine, said crank arm being slotted where it is attached to said rotatable part, whereby its throw may be adjusted, a pitman connecting said crank arm to the other member of said crank, said base plate having a slot, and fastening means extending through said slot into a part of said machine, permitting said base plate and the parts carried thereby to be adjusted relatively to said machine. 100 105 110 115
